Fig:2.

Fig: 1.

This cross-sectional view illustrates a double-acting cylinder assembly. The cylinder body is labeled 10, with a bore diameter of 20. The top piston is labeled 56, and the bottom piston is labeled 36. The top rod is labeled 42, and the bottom rod is labeled 46. The top cylinder is divided into two sections by a piston rod 30, with a bore diameter of 18. The top section is labeled 28, and the bottom section is labeled 52. The top cylinder is supported by a bearing 54, which is secured to a base plate 58. The bottom cylinder is supported by a bearing 48, which is secured to a base plate 50. The cylinder body 10 is mounted on a frame 22, which is supported by legs 24. The frame 22 has a height of 26. The cylinder body 10 has a height of 24. The top piston 56 has a height of 4, and the bottom piston 36 has a height of 4. The top rod 42 has a height of 26, and the bottom rod 46 has a height of 24. The top cylinder bore 18 has a height of 4, and the bottom cylinder bore 52 has a height of 4.

UNITED STATES PATENT OFFICE

2,619,621

ELECTRIC MOTOR AND SELECTOR SWITCH
THEREFORSteffen S. Brown, Dayton, Ohio, assignor to The
Brown-Brockmeyer Company, Dayton, Ohio,
a corporation of Ohio

Application October 4, 1950, Serial No. 188,454

4 Claims. (Cl. 318—202)

1

This invention relates to a switching device, and particularly to a switching device adapted for use with an electric motor to change the operating voltage and rotation thereof.

In the ordinary type split-phase motor or in a double voltage motor, whenever it is desired to change the operating voltage or the direction of rotation, it is necessary to remove the conduit or terminal box cover and then change the motor connections at the terminal plate. This, of course, is troublesome and involves the removing of the clamping nuts from the terminal posts and the changing of the leads thereon and then the replacing of the clamping nuts.

According to the present invention, this procedure is greatly simplified, and all chance of error in making such change eliminated by providing a switch which is mounted on the motor and which can be moved to a plurality of positions for effecting the desired changes in the motor connections.

Accordingly, the primary object of this invention is the provision of an arrangement for changing the operating voltage or the direction of rotation of an electric motor without the usual procedure of interchanging lead connections at the motor terminal posts.

A particular object is the provision of a switch for changing the terminal connections of an electric motor at any time desired.

Another particular object is the provision of a switching arrangement which can be built integrally with the motor structure and which is readily accessible externally of the motor for making changes in the motor lead connections.

These and other objects and advantages will become more apparent upon reference to the following description taken in connection with the accompanying drawings, in which:

Figure 1 is a perspective view of an electric motor showing a switch of the nature referred to mounted on the side of the motor;

Figure 2 is a view looking in at the switch from the side of the motor drawn at a somewhat larger scale than it is shown in Figure 1;

Figure 3 is a vertical section through the switch and is indicated by line 3—3 on Figure 2;

Figure 4 is another section looking in at the contact plates of the switch and is indicated by line 4—4 on Figure 3;

Figures 5, 6, and 7 are views similar to Figure 4 but showing the switch in other operative positions;

Figures 8, 9, 10, and 11 are wiring diagrams of a motor showing how the various motor leads

2

are connected to the terminal posts of the switch; and

Figure 12 is a fragmentary view showing how an overload protection relay can be included in the motor circuit.

Referring to the drawings somewhat more in detail, the electric motor shown in Figure 1 comprises the usual frame 10 within which are positioned the stator windings and also within which is rotatable an armature for driving the output shaft 12.

Power may be brought into the motor in any suitable manner, as by means of a conduit 14, and connected to the terminals of the windings within 15 in the motor frame.

According to my invention, the motor is additionally provided with a switching mechanism, generally indicated at 16, and to which all of the winding leads and the incoming power lines are 20 connected, so that adjustment of the switch will adjust the operating conditions of the motor.

A somewhat enlarged view of the switch is illustrated in Figures 2, 3, and 4, and in these figures it will be seen that the motor frame 10 is 25 preferably apertured, as at 18, in Figure 4, for permitting access to the terminal posts of the switch, to which the various leads of the motor windings and the power lines are connected. The switch mechanism may comprise a pair of spaced insulating members 20 and 22 spaced by the spacer sleeves 24 and secured to the motor frame as by screws 26. Any suitably strong insulating material, such as flock, fiber, or fabric-filled phenolic may be employed for the insulating disks. 30 Other substances well-known in the art may also be utilized for this purpose.

Mounted on member 20 are a plurality of studs 28 which are threaded on their one ends for receiving clamping nuts 30, and which have their 40 other ends rounded, as at 32, on the other side of the insulating member for being contacted by the contact elements of the movable part of the switch mechanism. The said movable part of the switch mechanism comprises an insulating disk element 34 having riveted or otherwise suitably affixed thereto the contact plates 36 and 38. As illustrated, rivets 40 secure the contact plates to element 34, but it will be understood that other means could be utilized, if desired.

Insulating disk 34 is suitably mounted on a shaft 42 which preferably has its opposite sides flat, as at 44, so that rotation of the shaft will also rotate the said disk. A spring 46 bears between insulating member 22 and the back of disk 50 34 and thereby continuously urges the said disk

toward the ends of studs 28 to hold contact plates 36 and 38 in good electrical contact with the said studs. A bushing 48 supports the one end of shaft 42, and nuts 50 secure the shaft against axial movement in one direction.

A shoulder 52 on the shaft on the opposite side of insulating member 20 provides a bearing for preventing axial movement of the shaft in the other direction and the said shaft is thus held in its proper location at all times while rotation thereof is permitted for adjusting disk 34.

The aperture 18 in the motor frame is enclosed by a cover plate 54 secured to the frame by screws 56 and through which the shaft extends for receiving the indicator 58. Indicator 58 has a pointed end 60 adapted for registering with the indicia 62 for indicating the operating conditions of the motor for each particular switch adjustment.

Inasmuch as the switch will ordinarily remain in an adjusted position for a considerable length of time, plate 54 may comprise a plurality of threaded holes 64 adapted for receiving a screw 66 extending through indicator 58, whereby the indicator may be locked in each of its operative positions.

Turning for the moment to Figures 8 through 11, there is shown the wiring diagram for a split-phase motor of the double voltage type having running windings 70 and 72 and a starting winding 74. The studs 28 which are mounted in insulating member 20 are connected with the terminals of the windings as illustrated. Thus, winding 70 has one end connected to the terminal marked 1, and its other end connected to the terminal marked 2; winding 72 has its one end connected with the terminal marked 3, and its other end connected to the terminal marked 4; and winding 74 has one end connected to the terminal marked 8, and its other end connected to the terminal marked 5.

Power line L1 is connected with the terminal 1, and power line L2 is connected with terminal 4. All other connections between the terminals are effected by the contact plates 36 and 38 of the selector switch of this invention.

At this point it may be noted that the switch layouts of Figures 4 through 7 each indicate seven terminals, and this is accounted for by the fact that two of the terminals are connected together, thus giving two connections for the terminal stud marked 2. This is done because it somewhat simplifies the construction of the contact plates of the switch.

It may also be pointed out that the order in which the terminal studs are indicated in Figures 8 through 11 is not the same as the order indicated in Figures 4 through 7, but this has been done for the purpose of clarifying the wiring diagram, and it will be understood that the identifying numerals applied to the terminal studs correspond for all of the views.

The motor for the diagram of Figures 8 through 11 may be a split-phase motor of the standard type, or a capacitor start motor, and in either case, the motor circuit will probably include a centrifugally operated switch of well-known construction whose function is to interrupt the circuit through the starting winding when the armature of the motor attains a predetermined speed.

This has been indicated in the drawings by the rectangle 76 which is intended to represent the centrifugal switch, or the combination of a condenser and a centrifugal switch, or any of

the other well-known means that may be employed for shifting the phase of the current in winding 74 or for interrupting the circuit through winding 74, or both.

It has been mentioned that this invention is adapted for use in connection with motors having an overload relay in circuit, and this is indicated in Figure 12, wherein there is placed in series with line L2 the overload relay 80, so that whenever the running winding of the motor becomes overloaded, the said relay will open and interrupt the supply of power to the motor. So far as the switch of this invention is concerned, the introduction of the overload relay involves no changes whatsoever.

Returning now to the switch proper, Figure 4 illustrates the manner in which the contact plates 36 and 38 are applied to insulating disk 34 and the actual relative positions of the terminal studs about the switch. It will be noted in Figure 4 that the terminal studs are generally located on two base circles which are radially spaced so the rivets 40 can be positioned on an intermediate base circle and thus prevent the rivets from interfering with the contacting of the studs by the contact plates.

In this manner it is insured that there will always be proper contact made and no undue wear on the studs or contact plates will occur. Contact plate 36 is a simple arcuate member extending about approximately 135 degrees of the periphery of the insulating disk 34 and having a notch 82 therein which will register with the one stud marked 2, as will be seen in Figure 6.

The other contact plate 38 extends about slightly more than 180 degrees of the periphery of the disk 34 and has its ends spaced from the ends of contact plate 36. Contact plate 38 is notched, as at 84, for the purpose of clearing the contact studs marked 1 and 2 in certain positions of the switch, as will be seen in Figures 4 through 7.

Operation

In order more fully to disclose the nature and operation of the switching arrangement of this invention, reference may be had to Figures 4 through 7 taken in connection with Figures 8 through 11, respectively.

In Figure 4 the switch is shown adjusted to the position where the operating voltage is 110 and the direction of rotation is counterclockwise. With the switch in this position, terminals 1, 3, and 5 are connected together and terminals 2, 4, and 8 are connected together. Inasmuch as line L1 is connected to terminal 1 and line L2 is connected to terminal 4, this results in the arrangement disclosed in Figure 8, wherein the running windings 70 and 72 are in parallel with each other and with starting winding 74.

To adjust the motor to counterclockwise rotation with the same voltage obtaining, the switch may be indexed in a clockwise direction by removing the screw 66 and turning the indicator so that pointer 60 points to the index on the 110 voltage side marked CW. The connections that then obtain are illustrated in Figure 9 and are identical with those of Figure 8, except that winding 74 has been reversed relative to windings 70 and 72, and a reverse direction of rotation is thereby obtained.

When the operating voltage of the motor is to be changed from 110 to 220 volts, the indicator 58 of the switch is rotated until pointer 60 is on the 220 volt side. When the pointer points to the index marked CC on the 220 volt side, the

connections shown in Figures 6 and 10 are obtained. In this case, terminals 2, 3, and 5 are connected together and terminals 4 and 8, with terminal 1 not being interconnected with any of the others.

Reference to Figure 10 will indicate that the running windings 70 and 72 are now in series between the power lines L1 and L2, and that the starting winding 74 is in parallel with running winding 72. Thus, each of the running windings is subjected to 110 volts, as well as the starting winding. It will be noted in Figure 6 that the notch 82 is in register with the terminal stud 2 toward the right-hand side of the view, and that the terminal stud 2 toward the left-hand side of the view is in engagement with contact plate 38.

In order to adjust the motor to clockwise rotation under 220 volts, indicator 58 of the switch is turned until its pointer 60 points to the index marked CW on the 220 volt side. The position of the switch that this produces is illustrated in Figure 7 and the motor connections in Figure 11.

It will be noted that terminal 1 is still not connected to any of the others of the terminals, that terminals 2, 3, and 8 are connected together, and that terminals 4 and 5 are connected together. The conditions within the motor are then the same as in Figure 10, except that starting winding 74 is reversed relative to the running windings 70 and 72.

It will be seen from the foregoing that my invention provides for a relatively simple switching arrangement for incorporation in a split-phase electric motor which makes it very convenient to change the operating voltage of the motor or to change its direction of rotation without the necessity of ever having to change the connections at the terminal box of the motor in the customary manner.

The switch is inexpensive to manufacture and can readily be incorporated in a motor structure at the time of manufacture. The switch is accessible for adjustment at all times and is adapted for being locked in each position of adjustment, thereby insuring that the switch can not accidentally become moved to an improper location.

The arrangement of my invention has been described and disclosed in connection with the usual type single-phase double voltage split-phase motor. It has been explained how it can be used with either a straight split-phase motor or with a capacitor start motor, but it will be understood that this invention is also adaptable for other types of motors, for example, double voltage two-phase motors, double voltage three-phase motors, as well as electrical reversible motors and other types where changes in motor connections are made to adapt the motor to different usages, are all ideal subjects for combination with a switching device according to my invention.

It will be understood that this invention is susceptible to modification in order to adapt it to different usages and conditions, and, accordingly, it is desired to comprehend such modifications within this invention as may fall within the scope of the appended claims.

I claim:

1. In combination: an electric motor having a frame with a stator therein having a plurality of windings with terminals, an aperture in the wall of the frame, a terminal plate mounted over the aperture inside said frame having a plurality of terminal posts to which said termi-

nals are individually connected, said plate forming a part of a switch comprising a movable part having contact members thereon engaging said posts to connect the windings, a shaft connected with the movable part extending out said aperture, said part being movable by actuation of the shaft to change the windings from series to parallel connection and to reverse the direction of rotation of the motor, an indicator on the outer end of said shaft, and a cover plate closing said aperture and bearing indicia to register with said indicator, the space between the terminal plate and cover plate defining a space for receiving the wires to be connected to the terminal posts.

2. In combination with an electric motor having a pair of running windings and a starting winding all with terminals, said motor having a frame with an aperture in one wall, a terminal plate mounted in the frame over the aperture having posts to which said terminals are individually connected, said plate forming a part of a switch comprising a single movable part having contact members thereon engaging said posts, a shaft connected to said part and extending out the aperture, said movable part having a first pair of positions wherein all of the windings are in parallel for operation of the motor at a lower voltage and a second pair of positions where the running windings are in series and with the starting winding in parallel with one thereof for operation of the motor at a higher voltage, said starting winding being connected in circuit in one direction for one of each of said pairs of positions and in the opposite direction for the other of each pair of positions, whereby either direction of operation of the motor can be had for either voltage, a cover plate outside the frame closing said aperture and through which said shaft extends, a combination indicator and turning knob on the outer end of the shaft, indicia on the cover plate to indicate the four operative positions of the said movable part, and means for clamping the indicator to the cover plate in only the said four positions.

3. In combination: an electric motor having a frame with a stator therein having a plurality of windings with terminals, an aperture in the wall of the frame, a terminal plate mounted over the aperture inside said frame having a plurality of terminal posts to which said terminals are individually connected, said plate forming a part of a switch comprising a movable part having contact members thereon engaging said posts to connect the windings, a shaft connected with the movable part extending out said aperture, said part being movable by actuation of the shaft to change the windings from series to parallel connection and to reverse the direction of rotation of the motor, an indicator on the outer end of said shaft, and a cover plate closing said aperture and bearing indicia to register with said indicator, means for locking said indicator to said cover plate in each position of said movable part, the space between the terminal plate and cover plate defining a space for receiving the wires to be connected to the terminal posts.

4. In combination: an electric motor having a frame with a stator therein having a plurality of windings with terminals, an aperture in the wall of the frame, a terminal plate mounted over the aperture inside said frame having a plurality of terminal posts to which said terminals are individually connected, said plate forming a part of a switch comprising a movable part having

contact members thereon engaging said posts to connect the windings, a shaft connected with the movable part extending out said aperture, said part being movable by actuation of the shaft to change the windings from series to parallel connection and to reverse the direction of rotation of the motor, a back plate spaced from said terminal plate behind said rotatable member for supporting said shaft and spring means positioned between said movable member and said back plate for urging said contacts against said posts, an indicator on the outer end of said shaft, and a cover plate closing said aperture and bearing indicia to register with said indicator, the space between the terminal plate and cover plate defining a space for receiving the wires to be connected to the terminal posts.
